CLAIM

The ornamental design for a canard dihedral fishing kite, as shown and described.

DESCRIPTION

FIG. 1 is a front perspective view of the canard dihedral fishing kite of the instant invention;

FIG. 2 is a rear perspective view thereof;

FIG. 3 is a bottom view thereof;

FIG. 4 is a top view thereof;

FIG. 5 is a left side view thereof;

FIG. 6 is a right side view thereof;

FIG. 7 is a rear view thereof;

FIG. 8 is a front end view thereof; and,

FIG. 9 shows an example of the design in use.

The portions of the Figures illustrated in broken lines form no part of the claimed subject matter.

1 Claim, 9 Drawing Sheets
